Attorney

UNITED STATES PATENT OFFICE.

LEO S. WHITEHEAD, OF AKRON, OHIO.

WRENCH.

Application filed May 6, 1922. Serial No. 558,895.

My invention relates to wrenches, and particularly to the class of wrenches designed for use in conjunction with pipe or pipe couplings.

5 Broadly, the invention has for its principal object the provision of a practical form of wrench which is constructed for operation to grip quickly and positively an object with a minimum amount of adjustment and manipulation of its elements.

More specifically, the invention is directed toward providing a wrench which may be set to an approximate adjustment relative to an object, and which, upon a slight and 15 quickly effected movement of one of its component parts, will securely grip the object and effect substantially a locked relation of its several parts, the construction of the parts being such that the greater the force 20 exerted on the wrench, the more tightly will it grip the object between its jaws. While the gripping action is strong, the wrench may be easily released from its hold on the object.

25 Other objects and advantages, such as simplicity of structure and ease of operation will presently appear and the nature of the invention will be more fully understood when the following description is read in conjunction with the drawings accompanying and forming a part of this specification, and in which,

Fig. 1 is a side elevational view, with parts broken away and showing in section, illustrating a wrench constructed in accordance with my invention;

Fig. 2 is a front elevational view illustrating a portion of my wrench;

Fig. 3 is a fragmentary side elevational view, parts showing in section, illustrating the manner in which my wrench is initially adjusted relative to an object;

Fig. 4, is a view similar to Fig. 3 illustrating further the operation of my invention; and

Fig. 5 is a detail side elevational view of one of the details of the invention.

In the preferred practice of my invention, my improved wrench comprises a tubular 50 handle, designated by the numeral 1, that is open at its upper end to receive the shank 2 of a jaw 3, the shank 2 being arranged for sliding movement longitudinally of the handle, in the usual manner, and provided 55 upon its front edge with a series of teeth 4 for a purpose presently apparent. Upon the

forward face of the handle 1, at a suitable point adjacent its open end a pair of outstanding ears 5 are provided between which a pivot pintle 6 extends. At its upper end 60 the handle is formed in the arc of a circle struck from the center of the pin 6 to provide upon each side of the shank 2 a curvilinear surface or seat one of which is shown at 7. Pivotaly mounted upon the pintle 6 65 is a T-shaped element 8 comprising a shank 9 that in the normal position of the element parallels the shank 2, and a transversely extending head that forms a second jaw 10 for cooperation with the jaw 3. The shank of 70 the element 8 is bifurcated at its lower end and slotted as at 11 to receive the pintle 6 whereby said element is movable transversely or oscillates upon the pintle for a purpose presently described. The head or jaw portion 75 10 of the element 8 is constructed to provide a substantially straight portion 12 having rearwardly spaced extensions one of which is shown at 13. The extensions 13 are curved to provide cam surfaces 14 leading 80 to the straight portion of the jaw and are adapted in the normal position of the element 8 to seat upon the seats 7 of the handle 1 at the sides of the shank 2. If desired, the handle 1 may be provided at its 85 upper end with spaced ears 15 to receive the shank of the element 8 and prevent lateral movement of the element in its normal position, relative to the handle.

Upon the pintle 6 and between the bifurcations of the elements 8, a toothed wheel 16 is mounted to project through a slot 17 in the handle 1 into engagement with the teeth 4 of shank 2. Wheel 16 is designed to move the shank 2 relative to the handle 1 and to 90 be rotated either directly by the operator or through movement of the oscillatable element 8 as will presently be explained. In order to effect the latter operation the element 8 is provided as at 18 with teeth forming an arc-shaped rack adapted to engage 95 with the teeth of the wheel 16, when the element is in its normal position relative to the wheel. A suitable form of spring 19 is coiled about the pintle 6 and is arranged in 100 position to bear against the shank 9 of the element 8 and the handle 1 to yieldingly retain the element in such position that its shank 9 parallels the shank 2 and its jaw 10 105 parallels the jaw 3, 110

The preferred manner of operating my invention is as follows: The operator by vir-

ture of the slots 11 in the shank of the element 8, may disengage the teeth 18 of said element from the teeth of the wheel 16, swing the element upon the pintle 6 into the position shown in Fig. 3, and adjust the shank 2 and jaw 3 relative to the jaw 10 of the element to position approximately the jaws relative to an object such as a pipe 20. The first part of this operation may be readily 10 accomplished by simply pressing the finger in an upward direction against the rear end of the extensions 13 whereupon the wheel 16 being free to rotate, the shank 2 and jaw 3 will gravitate normally into contact with 15 the pipe or object. Element 8 is now forced in the direction of the pintle to engage the teeth 18 with the wheel 16 as shown in full lines in Fig. 4. In this position the extensions 13 present their cam surfaces 14 to the 20 object. Element 8 is now rocked or oscillated upon the pintle 6 toward the shank 2 into its normal position as shown by the dotted lines in Fig. 4. This latter movement effects a rotation of the wheel 16 in a direction to move the shank 2 inwardly of the handle 1, whereupon the jaw 3 is drawn toward the jaw 10 at the same time that a cam engagement of the jaw 10 is being effected with the object 20. It will be noted that in 30 this latter movement of the jaw 10 it is sustained by the extensions 13 upon the curvilinear seats or surfaces 7 of the handle 1, and that as the shank 9 of said element reaches a dead-center position relative to the pintle 35 6 and the center of the object, the element is virtually locked in position against displacement. When the wrench is not in use the element 8 is obviously retained in this latter position by virtue of the action of the 40 spring 19. At whatever point the two jaws clamp the object, a rotation of the handle of the wrench in operation will tend to move the swinging jaw 10 toward the handle, and as the teeth 18 are normally in engagement with the wheel 16, the upper jaw 3 will be 45 caused to travel toward the lower jaw. The object is thereby securely clamped in position between the two jaws of the wrench and the operation of the wrench will securely grip the object. When it is desired 50 to release the object, a pressure on the extensions 13 will move the lower jaw outwardly and raise the upper jaw.

Although a preferred embodiment of my invention has been described in detail and certain restrictive terms and language employed herein, it is to be understood that the present disclosure is illustrative in nature and is not to be construed as limiting the scope or spirit of my invention unless such limitations are specifically expressed in the claims appended hereto.

What I claim is:

1. A wrench comprising, a handle, a jaw 65 member movable longitudinally of the han-

dle, a second jaw member movable laterally of the first member into gripping position with respect thereto, and means for moving the first member toward the second member upon movement of the latter into gripping position relative to the former, said means comprising a rack upon the first named jaw, a pinion rotatably mounted on the handle and meshing with the rack and a rack on the second jaw movable into and out of engagement with the pinion.

2. A wrench comprising, a handle, a longitudinally movable jaw member, a second oscillatable jaw member pivoted on the handle and movable laterally of the first member into and out of gripping position with respect thereto, and means for moving the first member toward said second member operated by movement of said second member toward gripping position.

3. A wrench comprising, a handle, a jaw member movable longitudinally of the handle, a second jaw member adapted for oscillating movement laterally of the first member and having a cam gripping surface, and means for moving the first member toward the second member upon movement of the second member in one direction, said means comprising a rack on the first named jaw, a pinion engaging said rack and an arc-shaped rack on the second jaw, the second jaw and the pinion having a common center of movement.

4. A wrench comprising, a handle, a jaw member movable longitudinally of the handle, a second jaw member yieldingly held in gripping position with respect to the first member and adapted for oscillating movement into and out of such gripping position, means for moving the first member toward the second upon movement of the latter into gripping position, and means for rendering said latter means inoperative.

5. A wrench comprising, a handle, a jaw member freely movable longitudinally of the handle, a second jaw member yieldingly held in gripping position with respect to the first member said second member being adapted for movement laterally of the first member to adjust it into and out of gripping relation with respect thereto, and a pinion carried by the handle and adapted to be connected with both of said jaw members for moving the first member toward the second during the entire movement of the latter into gripping position.

6. A wrench comprising, two jaw members movable toward and away from one another, a rack on one of said jaw members, a pinion engaging said rack, and a second rack on the other jaw member, the last named jaw member having a center of oscillation coinciding with the center of the pinion and being movable to engage or disengage its racks from the pinion.

7. A wrench comprising, two jaw members, one of said members being pivotally mounted, a straight rack on one of said jaw members, a curved rack on the other jaw member, and a pinion adapted to be engaged by one or both of said racks.

8. A wrench comprising, a rectilinearly moving jaw member and an oscillatory jaw member, a straight rack on the first jaw member and a curved rack on the second jaw member, and a pinion adapted to be engaged by one or both of said racks.

9. A wrench comprising, a tubular handle having a curvilinear seat at one end thereof, a jaw member having a toothed shank slidably mounted in the handle, a rotary wheel upon the handle having teeth thereon engaging the teeth of said shank, a second jaw member comprising a curvilinear head portion adapted to normally engage the seat of said handle and a shank portion mounted for swinging movement about the axis of the wheel said last shank being constructed to engage or release the wheel, and lugs upon the handle adapted to prevent lateral movement of the second jaw.

10. A wrench comprising, a handle, a jaw member movable longitudinally thereof, a

rotary member for moving the jaw, means for actuating the rotary member, and a second jaw member adapted for oscillation about the axis of the rotary member and for adjustment to engage and release said rotary member.

11. A wrench comprising, a handle, a jaw member movable longitudinally thereof, a rotary member for moving the jaw, and a second jaw member adapted for oscillation about the axis of the rotary member, said second jaw being adapted normally to engage the rotary member, for rotary movement therewith in all of its positions of longitudinal movement.

12. A wrench comprising, a handle, a jaw member movable longitudinally thereof, a rotary member for moving the jaw, and a second jaw member adapted for oscillation about the axis of the rotary member for movement into and out of a dead center position relative to said axis and the first jaw said second jaw being adapted to engage the rotary member throughout its entire oscillatory movement, and means for yieldingly retaining the second jaw in a dead center position.

LEO S. WHITEHEAD.
